(57) **CLAIM**

The ornamental design for a ceiling fan light kit as shown and described.

DESCRIPTION

FIG. 1 is a top perspective view of a ceiling fan light kit in the environment of a ceiling fan, showing my new design; FIG. 2 is a top perspective view of the ceiling fan light kit with the ceiling fan environment of FIG. 1 removed; FIG. 3 is a top view thereof;

FIG. 4 is a bottom view thereof;

FIG. 5 is a front side view thereof;

FIG. 6 is a rear side view thereof;

FIG. 7 is a left view thereof; and,

FIG. 8 is a right view thereof.

Portions of the ceiling fan, the ceiling fan environment, and the ceiling fan light kit are shown in broken lines. Portions shown in broken lines form no part of the claimed design.

1 Claim, 8 Drawing Sheets
